US00D912624S

(12) **United States Design Patent** (10) **Patent No.:** **US D912,624 S**
Chung (45) **Date of Patent:** **** Mar. 9, 2021**

(54) **FERRITE CORE**

(71) Applicants: **LITE-ON ELECTRONICS (GUANGZHOU) LIMITED**,
 Guangzhou (CN); **LITE-ON TECHNOLOGY CORPORATION**,
 Taipei (TW)

(72) Inventor: **Chao-Lin Chung**, Taipei (TW)

(73) Assignees: **LITE-ON ELECTRONICS (GUANGZHOU) LIMITED**;
LITE-ON TECHNOLOGY CORPORATION

(**) Term: **15 Years**

(21) Appl. No.: **29/712,401**

(22) Filed: **Nov. 7, 2019**

(30) **Foreign Application Priority Data**

Aug. 30, 2019 (TW) 108305277
 Oct. 15, 2019 (TW) 108305277D01

(57) **CLAIM**

The ornamental design for a ferrite core, as shown and described.

DESCRIPTION

FIG. 1 is a perspective view of a ferrite core showing my new design;

FIG. 2 is a front view thereof;

FIG. 3 is a rear view thereof;

FIG. 4 is a left side view thereof;

(Continued)

FIG. 5 is a right side view thereof;
FIG. 6 is top plan view thereof; and,
FIG. 7 is a bottom plan view thereof.

1 Claim, 7 Drawing Sheets
